UNITED STATES PATENT OFFICE.

ALEXANDER L. MUNRO AND HARVEY H. RUMPEL, OF MILWAUKEE, WISCONSIN,
ASSIGNORS TO SMITH ENGINEERING WORKS, OF MILWAUKEE, WISCONSIN, A
CORPORATION OF WISCONSIN.

PRIMARY BREAKER.

Application filed October 15, 1923. Serial No. 668,485.

To all whom it may concern:

Be it known that we, ALEXANDER L. MUNRO and HARVEY H. RUMPEL, citizens of the Dominion of Canada and of the United States, respectively, the former a subject of the King of Great Britain, both residing at Milwaukee, in the county of Milwaukee and State of Wisconsin, have invented a certain new and useful Improvement in Primary Breakers, of which the following is a specification.

Our invention relates to improvements in gyratory crushers and has for one object to produce a simple and efficient lubricating means for such a crusher. Another object is the improvement of bearings of such a crusher. Another object is the improvement of the head adjustment of such a crusher. Other objects will appear from time to time 20 in the course of the specification and claims.

We illustrate our invention more or less diagrammatically in the accompanying drawings, wherein:

Figure 1 is a vertical view through the machine; and

Figure 2 is a section on the line 2—2 of Figure 1.

Like parts are illustrated by like characters throughout the drawings and specification.

A is a crushing hopper mounted on a base A¹ and provided on its interior with a crushing lining A², the whole being mounted upon a foundation A³. A⁴ is a lower spider secured to the base and in this instance integral with the base of the crusher and adapted to support the central shaft A⁵ which is secured to it and supported at its upper end by the upper spider A⁶ which is integral with the feed hopper A⁷ secured to the crusher hopper A by the bolts A⁸.

B is a driving shaft upon which is mounted the belt pulley B¹ adapted to be driven by any suitable source of power not here shown. B² is a miter pinion on the shaft B rotating in the oil pocket B³. It is in mesh with the miter gear B⁴ keyed to the eccentric sleeve B⁵ which in turn is mounted for rotation about the fixed central shaft A⁵ and is supported at its lower end upon the thrust bearing B⁶. B¹⁰ is a miter gear keyed to the shaft B and meshing with the motor gear B¹¹ on the vertical pump shaft B¹² which communicates with the pump not herein

shown, which is adapted to deliver lubricant 55 to the crusher. B¹³ is a return passage from the oil pocket B³ to said pump.

C is a crushing head floating upon the eccentric sleeve B⁵. It is provided with a depending stem or shank portion C¹ which 60 fits inside and is slidably keyed to the adjustment plate C² and terminates above the miter gear B⁴ earlier mentioned. The adjustment plate C² is mounted upon the supporting ring or table C⁵ which in turn is 65 mounted upon the lower spider A⁴. C⁶, C⁷ is any suitable packing or channelling to prevent oil leakage between said plate and table. C⁷, C⁸ are supporting brackets projecting upwardly from the surface of the 70 adjustment plate C² and are provided with dowel holes C⁸. They are adapted to receive adjusting shims C⁹ of varying thicknesses, which in turn are provided with dowels C¹⁰ adapted to penetrate said holes C⁸. Upon 75 the upper surfaces of said shims rests the under surface C¹¹ of the crushing head C. C¹², C¹³ are port-holes with gates C¹³, C¹⁴, giving easy access to the adjusting ring and shims. 80

D is a main lubricating supply pipe leading from a pump not here shown, to the lower bearing of the central shaft A⁵. D¹ is an inwardly tapered bushing or sleeve, the inner surface of which is adapted to 85 contact the tapered reduced end D² of said central shaft. The sleeve is secured in position by means of the plate D³ which contacts its bottom, and is drawn against the shaft by the bolt D⁴, which is screw threaded into the bottom of said shaft, and the nuts D⁵. D⁶ is any suitable protecting casting. Said sleeve is apertured as at D⁷ at substantially the height of the inlet of the oil pipe D. At the same height the interior 90 of the frame is circumferentially grooved as at D⁸ and the tapered portion of the central shaft A⁵ is circumferentially grooved as at D⁹. D¹⁰ is a lubricating supply pipe adapted to deliver lubricant to the chamber 95 D¹¹ about the shaft B.

The crushing head C is provided at its top with a packing ring F, the bottom of which engages a packing surface E¹ on the top of said crushing head, adapted to make a substantially oil tight joint. The pressure is exerted upon the packing ring to assist in the oil tightness of this joint by 105

means of the screws E² which insure a firm fitting of the packing ring on the upper end of the crushing head.

The center shaft A⁵ is axially pierced by 5 a central oil passage G which extends from the bottom of the shaft to a point near the top, the bottom of said passage being closed, for example, by the bolt D⁴ earlier mentioned. Oil inlet ducts G¹ extend from said 10 passage to the slot D⁹. Oil outlet ducts G², G³ radiate from said passage G at various points along the length of the shaft. The eccentric sleeve G⁵ is pierced by similar oil passages G⁴, G⁵.

15 Between the central shaft and the eccentric and between the eccentric and the crushing head are babbitt sleeves or bearings each of which consists of two staves or substantially semi-cylindrical segments, respectively shown in Figure 2 as H, H¹ and H², H³. Each segment is formed with an integral key H⁴, received in a corresponding recess, adapted to prevent rotation of the bearing as a whole and relative movement 20 of the two halves of the bearing. The staves are provided with oil holes H⁵, H⁶ in opposition to the oil passages G², G³, G⁴, G⁵ earlier described.

25 The babbitt segments H¹, H² are supported at the bottom by the shoulder B²⁰ inwardly projecting from the bottom of the eccentric sleeve. They are held at the top by a snap ring B²¹ seated in a circumferential groove B²² in the top of the eccentric 30 sleeve. The babbitt segments H², H³ may be similarly held in place, for example by the circumferential shoulder C²⁰ projecting inwardly about the bottom of the head C and any suitable ring about the top of the 35 head.

40 I is a downwardly and outwardly inclined oil duct through the shank portion C¹ of the crushing head which terminates in alignment with the passage or opening I¹ in the adjustment plate C². I² is a downwardly and inwardly inclined oil passage 45 through the supporting ring or table C⁵ adapted to deliver any oil which passes over the surface of said table to the oil pocket B³.

50 J is an adjusting saddle adapted to be aligned with the top of the central shaft A⁵ and to be supported upon the lock nut at the top thereof. It is provided with depending hook bolts J¹ the lower hook ends J² of which are adapted to be hooked under the edges of the crushing head. J³ are nuts, the rotation of which is adapted to raise 55 or lower the hook bolts J¹ in relation to the yoke or saddle J.

60 The counter shaft is mounted for rotation in bearings K, K¹ which are each cast with an integral key which fits into a key seat cut in the counter shaft sleeve K².

65 It will be realized that while we have illustrated a working device, many changes

might be made in the size, shape, number and disposition of parts without departing from the spirit of our invention and we therefore wish our description and drawings to be taken in a large sense diagrammatic. 70

The use and operation of our invention are as follows:

The material to be crushed is fed into the crusher through the feed hopper from above and passes into the crushing hopper where it is crushed by the gyration of the crushing head. The crushed material as it becomes small enough falls out at the bottom through the aperture between the crushing head and the hopper walls. This aperture may be 75 kept at uniform size as the crushing head or the crushing walls wear by raising the crushing head. This adjustment is accomplished by first lifting the crushing head by means of the yoke J and the hook bolts J¹. 80 Shims of a suitable size are then inserted, being placed upon the supporting surfaces C⁷ where they are held against lateral movement by the dowel pins penetrating dowel holes. When shims of the proper thickness 85 have been placed on all of said platforms, the crushing head may be lowered into position. This method of head adjustment insures an accurate alignment of the head, 90 since the position of the head may be absolutely controlled by controlling the thickness of the shims. This accurate alignment insures equal pressure on the babbitt bearings between head and eccentric and between eccentric and central shaft. Where other 95 and less accurate methods of adjustment are used cracking and wearing of the babbitts is common as a result of an inaccurate alignment of the head splitting the babbitt. This accurate alignment of the head also prevents 100 oil leakage from about the top of the head. This is particularly important since the lubricant is pumped under pressure through the central shaft and the pressure of the lubricant together with the centrifugal motion 105 given it by the rotation of the eccentric makes oil leakage a vital problem.

A pump driven from the shaft B circulates oil under pressure through the crusher, the lubricant passing through the pipe D to the bottom of the central shaft where it communicates with the circumferential groove D⁸. This groove is aligned as to height with the groove D⁹ about the tapered bottom of the shaft. The tapered bearing or sleeve 115 D¹ is apertured at the same height as the two circumferential grooves and the adjustment of said bearing is therefore automatic, 120 since all that is necessary is to insert it between the tapered bottom of the shaft and the cylindrical socket in the spider into which it fits. In the past it has been necessary to make a careful adjustment of the oil passage inlet with the parts or passages in the central shaft with which it communi- 125 130

cates. Applicants' structure avoids these difficulties and makes it impossible for even the most unskilled laborer to assemble applicants' crusher without keeping the oil inlet 5 passage open. The oil passing about the slot D⁸ through the passage D⁷ and into the passage D⁹ then finds its way through the inlet passages G¹ to the main axial oil passage G, running up through the center of the 10 central shaft. Branch distribution passages G², G³ deliver the lubricant to the bearing surfaces and the passages G⁴, G⁵ to the eccentric carry the lubricant to the outer bearing between the eccentric and the head; the head 15 being accurately aligned and adjusted, the sleeve E may be compressed by the screws E² against the packing surface E¹ and leakage is substantially completely prevented. The lubricant drains down into the oil pocket B³ 20 and is drawn through the passage B¹³ back to the pump where it is settled and filtered by any suitable means not herein shown and subsequently returned under pressure to the crusher.

25 The eccentric rotates between babbitt bearings or sleeves, each of which is composed of two substantially semi-cylindrical segments or staves; each of said segments is provided with an axial key which is received in a corresponding axial groove in the crushing head and the eccentric respectively as shown in Figure 2. It will be noted that the keys and key ways are positioned at the point of minimum throw. This is particularly important 30 since it prevents a concentration of pressure at the key and prevents the splitting of the babbitt down the key, the key being the point of greatest danger of splitting of the babbitt staves. The keys hold 35 the individual segments firmly in position and as they are cast with properly located oil holes, the oil passages H⁵ are accurately aligned with the lubricant passages G⁴, G⁵ in the eccentric.

40 We claim:

1. In a crusher, a hopper, a central shaft, and a crusher head, adapted for eccentric motion thereabout, and a babbitt bearing intermediate the central shaft and the crusher 45 head comprising a pair of substantially semi-cylindrical sections, each section being formed with an integral longitudinal key.

2. In a crusher, a hopper, a central shaft, and a crusher head adapted for eccentric motion thereabout, and a bearing comprising a pair of substantially semi-cylindrical sections, each section being provided with a longitudinal key substantially removed circumferentially from the point of maximum throw.

3. In a crusher, a hopper, a central shaft, and means for supporting it, an eccentric mounted about said shaft and means for rotating it, a crusher head floating on said shaft about said eccentric, and babbitt bear-

ings intermediate the central shaft and the crusher head comprising a pair of substantially semi-cylindrical sections, each section being formed with an integral longitudinal key.

4. In a crusher, a hopper, a central shaft, and means for supporting it, an eccentric mounted about said shaft and means for rotating it, a crusher head floating on said shaft about said eccentric, and bearings between shaft and eccentric comprising a pair of substantially semi-cylindrical sections, each section being provided with a longitudinal key substantially removed circumferentially from the point of maximum throw.

5. In a crusher, a hopper, a central shaft, and means for supporting it, an eccentric mounted about said shaft and means for rotating it, a crusher head floating on said shaft about said eccentric, and babbitt bearings between said shaft and said eccentric, and said eccentric and said head comprising each a pair of substantially semi-cylindrical sections, each section being formed with an integral longitudinal key.

6. In a crusher, a hopper, a central shaft, and means for supporting it, an eccentric mounted about said shaft and means for rotating it, a crusher head floating on said shaft about said eccentric, and bearings between said shaft and said eccentric, and said eccentric and said head comprising each a pair of substantially semi-cylindrical sections, each section being provided with a longitudinal key, the keys of the bearing between the shaft and eccentric being substantially removed circumferentially from the point of maximum throw.

7. In a crusher, a hopper, a central shaft, and means for supporting it, an eccentric mounted about said shaft, and means for rotating it, a crusher head floating on said shaft about said eccentric, and bearings between said head and said eccentric comprising a pair of semi-cylindrical babbitts, each separately keyed to the inside wall of said head.

8. In a crusher, a hopper, a central shaft and means for supporting it, an eccentric mounted about said shaft, and means for rotating it, a crusher head floating on said shaft about said eccentric, and bearings between said head and said eccentric comprising a pair of semi-cylindrical babbitts, and a longitudinal key extending substantially from end to end of each of said babbitts, the inside wall of said head being channelled to receive them.

9. In a crusher comprising a hopper, a central shaft and means for supporting it, a crushing head mounted on said shaft and means for vertically adjusting and for aligning it, comprising an element adapted to support the crushing head, a plurality of shim supporting pads upwardly projecting

from said element and spaced thereabout and a plurality of independent adjustable shims spaced about said element and positioned upon said pads and interposed between them and the crushing head, the crushing head extending downwardly through said supporting element and depending substantially therebeneath.

10. In a crusher comprising a hopper, a central shaft and means for supporting it, a crushing head mounted on said shaft, and means for vertically adjusting and aligning it, comprising a ring adapted to support the crushing head, shim supporting pads upon the upper side of said ring and projecting a substantial distance thereabove, and a plurality of adjustable shims interposed between said pads and the crushing head, the said shims being fixed by dowel pins against lateral movement in relation to said pads.

11. In a crusher comprising a hopper, a central shaft and means for supporting it, a crushing head mounted on said shaft, and means for vertically adjusting and aligning it comprising a ring adapted to support the crushing head, shim supporting pads upon the upper side of said ring and projecting a substantial distance thereabove, located at a plurality of separate points about the circumference of said ring, and a plurality of adjustable shims adapted to be interposed between said pads and the crushing head.

12. In a crusher comprising in part a hopper, a fixed central shaft, a rotating eccentric and a crushing head mounted about said eccentric, and a shaft and a driving connection between said shaft and said eccentric, babbitt bearings between said shaft and head comprising a plurality of substantially cylindrical bushings, keys formed integrally therewith and adapted to prevent their rotation.

13. In a crusher comprising in part a hopper, a fixed central shaft, a rotating eccentric and a crushing head mounted about said eccentric, and a shaft and a driving connection between said shaft and said eccentric, bearings for said shaft comprising a plurality of substantially cylindrical bushings, keys cast integrally therewith and adapted to prevent their rotation, and means for lubricating said bushings comprising an oil inlet passage intermediate said bushings and an oil connection between it and each of said bushings.

14. In a crusher, a hopper, a central shaft, and a crusher head adapted for eccentric motion thereabout, and a bearing comprising a pair of substantially semi-cylindrical sections, each section being provided with a longitudinal key at least twenty-five degrees circumferentially removed from the point of maximum throw.

15. In a crusher, a hopper, a central shaft

and means for supporting it, an eccentric mounted about said shaft and means for rotating it, a crusher head floating on said shaft about said eccentric, and bearings between shaft and eccentric comprising a pair of substantially semi-cylindrical sections, each section being provided with a longitudinal key at least twenty-five degrees circumferentially removed from the point of maximum throw.

16. In a crusher comprising a hopper, a central shaft and means for supporting it, a crushing head mounted on said shaft, and a spider overlying said head, a telescoping ring mounted therein and adjustable means for holding said ring against the top of said head, and means for vertically adjusting and aligning said head, comprising a ring adapted to support it, shim supporting pads on the upper side of said ring and projecting upwardly a substantial distance from the surface thereof and a plurality of adjustable shims interposed between said pads and the crushing head, the crushing head extending downwardly through said supporting element and depending substantially therebeneath.

17. In a crusher comprising a hopper, a central shaft and means for supporting it, a crushing head mounted on said shaft, and a spider overlying said head, a telescoping ring mounted therein and adjustable means for holding said ring against the top of said head, and means for vertically adjusting and aligning said head comprising a ring adapted to support it, shim supporting surfaces on the upper side of said ring and a plurality of adjustable shims interposed between said surfaces and the crushing head, and a downward projection from said head passing through and depending beneath said supporting ring.

18. In a crusher, a hopper, a central shaft and a crusher head adapted for eccentric motion thereabout, and a bearing comprising a pair of substantially semi-cylindrical sections, each section being provided with a longitudinal key, the interior of the head being apertured to receive said keys, a shoulder inwardly projecting about the bottom of said head and adapted to support said sections, and a removable securing means about the top of said head.

19. In a crusher, a counter shaft and means for rotating it, a sleeve within which said shaft is mounted for rotation, a bearing mounted therein, a key integral with said bearing, the sleeve being slotted to receive said key.

Signed at Milwaukee, Wisconsin this 26th day of September, 1923.

ALEXANDER L. MUNRO.
HARVEY H. RUMPEL.
